(57) **CLAIM**

The ornamental design for a television telephone, as shown and described.

DESCRIPTION

FIG. 1 is a perspective view of a television telephone showing my new design;

FIG. 2 is a front elevation view thereof;

FIG. 3 is a rear elevation view thereof;

FIG. 4 is a left end elevation view thereof;

FIG. 5 is a right end elevation view thereof;

FIG. 6 is a top view thereof;

FIG. 7 is a bottom view thereof;

FIG. 8 is a cross-sectional view thereof, taken along line A—A' in FIG. 6, with inner structure omitted;

FIG. 9 is a cross-sectional view thereof, taken along line B—B' in FIG. 6, with inner structure omitted;

FIG. 10 is a cross-sectional view thereof, taken along line C—C' in FIG. 6, with inner structure omitted;

FIG. 11 is a cross-sectional view thereof, taken along line D—D' in FIG. 6, with inner structure omitted;

FIG. 12 is a cross-sectional view thereof, taken along line E—E' in FIG. 6, with inner structure omitted;

FIG. 13 is a side elevation view thereof wherein the arm and camera portions are in a housed condition; and,

FIG. 14 is a top plan view thereof showing the arm and camera portions in a housed condition.

The broken line showing of environmental features in FIGS. 4, 5, and 12 is for illustrative purposes only and forms no part of the claimed design.
